ABRAHAM J. SCHULTZ, OF NEWARK, NEW JERSEY

COLLAPSIBLE SIDE RAIL FOR BEDSTEADS

Application filed December 17, 1927. Serial No. 240,679.

This invention relates, generally, to improvements in the form and construction of side rails for bedsteads; and, more particularly, to collapsible side rails adapted when collapsed to be reduced to a length within the maximum dimensional limits of bed ends, so that the side rails may be stored, packed, shipped and delivered with the particular bed ends for which they are designed to be used.

10 Metal bedsteads comprise, essentially, four distinct separable parts, namely, a foot end, a head end and two side rails. The side rails in use must necessarily be somewhat longer than the height of the average person; that is, they are usually in excess of six feet long. In consequence of the length of the side rails, when made of the usual single or integral body, it has hitherto been found impractical to pack the same together with the bed ends 15 in one bundle, crate, or package for storage, shipment or delivery, since the extreme dimensions of the bed ends is less than six feet. The customary practice, pursued to the present time, has been to crate together and deliver together the bed ends and to separately ship and deliver the side rails in one or more 20 separate packages, bundles according to their number, with consequent risk of loss, mismatching, etc. The problem presented is to provide a form and construction of side rail which may be conveniently packed in pairs with the particular bed ends which they are to serve, thereby eliminating risk of loss, mismatching and various other inconveniences 25 which follows separate handling of bedstead side rails. Hitherto this problem has not been solved, despite the fact that the metal bedstead industry has been confronted by the same for upwards of twenty-five 30 years.

The failure to solve this problem has hampered the fullest development of the metal bedstead industry; and in order to understand the extent to which such failure has 35 been an obstacle to such development, the following facts must be considered.

In the first place the dealer in metal bedsteads who carries the makes of several different manufacturers in his line, finds himself in possession of various types and styles

of bed ends suitably crated for eventual delivery to his customers, but also finds himself in possession of an assortment of separate side rails of various types and designs, which cannot be promiscuously selected and used, but which must, on a sale of a bedstead, be carefully selected to mate with the latter. The dealer therefore must be particularly careful when delivering a bedstead to his customer, that proper side rails are selected for shipment. Even when reasonable care is exercised errors are constantly being made and mismatching side rails are frequently delivered, and, furthermore, side rails separately shipped become lost and are not finally delivered to the customer until after considerable trouble and delay. Owing to these difficulties dealers are discouraged from purchasing from various manufacturers, and usually confine their line to one or two of the latter, thus losing the advantages of competitive conditions in purchasing stock, while on the other hand the manufacturer is discouraged from using improved types of rails and coupling connections for assembling the same in the bedstead which might otherwise be profitably adopted.

If bed ends and properly mating side rails could be conveniently handled together at all times for storing, shipment, packing and delivery, the problems and difficulties above adverted to would be solved and overcome. To this end, therefore, it is the object of this invention, broadly, to provide a collapsible form of side rail which can be packed or crated together with bed ends so as to form one unit bundle which need not be opened from the time it leaves the factory until delivery to the ultimate customer. More specifically, the invention has for a further object to provide a preferred form and construction of collapsible side rail for bedsteads as hereinafter described, and which is adapted to furnish, when opened up and connected between the bed ends, a strong, durable and rigid construction capable of supporting the weight of springs, mattress and occupants as efficiently and safely as would the single or integral non-collapsible rail heretofore in use.

The present invention in one preferred

form is illustrated in the accompanying drawings, in which:—

Figure 1 shows a view in face elevation of bed ends and collapsible side rails therefor assembled together for packing in a single bundle.

Figure 2 is an inside side elevation of a preformed form of collapsible side rail in extended condition for operative engagement between bed ends; Figure 3 is an outside side elevation of the same; Figure 4 is a top plan view of the same; and Figure 5 is a bottom plan view of the same.

Figures 6 and 8 are fragmentary inside side elevations and part sectional views showing the manner of manipulating the fastening means of the collapsible joint between the rail sections, and Figures 7 and 9 are respectively cross sections taken on line 7—7 in Figure 6 and line 9—9 in Figure 8 respectively; Figure 10 is a horizontal sectional view taken on line 10—10 in Figure 6, and Figure 11 is a horizontal sectional view taken on line 11—11 in Figure 8; Figure 12 is a plan view showing the disposition of the rail sections preparatory to collapsing the same, and Figure 13 is a cross section taken on line 13—13 in Figure 12; Figure 14 is a fragmentary horizontal section showing the abutting ends of the sections in normal aligned condition, and Figure 15 is a similar view showing the lateral displacement of one section relative to the other preparatory to collapsing of the same; Figure 16 is an inside side elevation and part section showing the operation of collapsing the rail sections; Figure 17 is a similar view with the sections folded together in collapsed condition; and Figure 18 is a transverse vertical section, taken on line 18—18 in Figure 17.

Similar characters of reference are employed in all of the hereinabove described views, to indicate corresponding parts.

Referring to the drawings, the reference character 20 indicates one rail section and 21 the other rail section, which are interconnected together so that the same may be extended and interlocked together to provide a bedstead side rail of proper length for operative extension and interconnection between a head end 22 and a foot end 23 of a bedstead, or so that the same may be collapsed into a desired foreshortened condition convenient for packing with the bed ends in a manner similar to that shown in Figure 1 or in any other convenient or desirable manner. The outer ends of the respective rail sections 20 and 21 may be provided with suitable corner-lock elements 24 adapted to be engaged with cooperating corner-lock means with which the bed ends are provided, all in the manner familiar to those skilled in the art. Each rail section is preferably made of angle-iron to comprise a horizontal flange 25 and a vertical flange, and when said sections

are in normal extended and longitudinally aligned condition their inner ends are disposed in mutually abutting relation. Arranged within the angle of the abutting ends of each said sections 20 and 21 is a coupling member or center lock means in the form of an angle member, comprising a vertical portion 25 disposed across the joint between the sections so as to overlie the inner faces of the vertical flanges of said sections, and a horizontal portion 26 also disposed across the joint between said sections so as to lie against the underside of the horizontal flanges of the latter. At least one end of the vertical portion 25 possesses a rounded ear 26' to allow the adjacent rail section to swing or turn around the same when released for movement to collapsed relation to the opposite rail section. Said vertical portion 25 is secured at one end to the rail section 20 by a suitable fastening means, such as a bolt 27 and nut 28 over which the free end of the bolt shank is riveted, as at 29 or by means of a rivet, or by welding, since the connection may be of fixed character for the reason that no relative movement between the coupling member or center-lock means and one of the rail sections is required. The opposite end of said vertical portion 25 is movably secured to the rail section 21 by means of a bolt 30 and nut 31, the latter being adjustable on the former. Preferably the free end of the shank of said bolt 30 is crushed over, as at 32, to provide a stop against entire separation of the nut 31 therefrom.

The abutting ends of the horizontal flanges of the rail sections 20 and 21, are respectively provided with angular notches 33 and 34, which are normally opposed to each other so as to form a rectangular receiving socket to match and register with a similar rectangular receiving socket 35 provided in the underlying horizontal flange 26 of the coupling member or center lock means. The reference character 36 indicates the head of a keeper bolt, having a rectangular shoulder 37 beneath the head to extend into said receiving sockets above described, and having a threaded shank 38 extending downwardly from said shoulder portion. Movable engaged on said shank 38 is a fastening nut 39. Preferably the free end of said shank 38 is crushed over, as at 40, to provide a stop against entire separation of the nut 31 therefrom.

When the rail sections are opened out into operative extended relation for interconnection between the head and foot ends of the bedstead, the adjoining ends of the rail sections 20 and 21 are brought into aligned abutting relation and the keeper bolt is thrust downwardly to enter the rectangular shoulder 37 in the receiving socket provided by the opposed notches 33—34 of the rail section ends and by the opening 35 in the

horizontal flange of the coupling member or center lock means, the head of the keeper bolt abutting the upper faces of the horizontal flanges of said rail sections. When 5 the keeper bolt is thus disposed the fastening nut 39 is turned home on the shank 38 to abut the underside of the horizontal flange of said coupling member or center lock means. The nut 31 of the transverse 10 bolt 30 is turned home to securely draw together and retain the vertical flange of said rail section 21 against the vertical flange of the coupling member or center lock means, all as shown more especially in Figures 2 15 to 7 inclusive of the drawings. It will be observed that the fastening arrangement for joining the rail sections in operative extended relation assures a very strong and immovable interconnection thereof, particularly 20 since the abutting or meeting ends of the rail sections are securely aligned together and so retained that neither displacement in vertical or horizontal planes is possible. The strength of the connection thus formed is such that when the rail sections are operatively 25 engaged between the head and foot ends of the bedstead a strong and rigid arrangement is provided which is adequately capable of supporting the weight of springs, 30 mattress and occupants of the bed as efficiently and safely as would a single or integral non-collapsible rail heretofore in use.

When the side rails are disconnected from the bed ends the same may be collapsed so 35 as to reduce the length thereof to a dimension within a maximum dimensional limits of the bed ends, to thereby permit of the assembling of the bed ends and side rails in a single package for storage and shipping. 40 To so collapse the rail sections, in the form thereof illustrated in the drawings, the operator loosens the nut 39 of the keeper bolt and also loosens the nut 31 of the transverse bolt 30. When the bolts are thus loosened, 45 as shown in Figures 6 and 7, the keeper bolt is lifted to remove the rectangular shoulder 37 from the receiving sockets, and the transverse bolt 30 is thrust outward to space its head away from the exterior side of the rear section 21, this arrangement being shown in Figures 8 and 9. The operator may now 50 move the rail section 21 sidewise relative to the side rail 20 so that the abutting vertical ends of the respective rail sections are disposed out of alignment. This movement is 55 also permitted by reason of the play between the notches and the keeper bolt shank 38 as shown in Figure 12. The relative sidewise displays of the rear section 21 with respect to the rail section 20 is illustrated in 60 Figures 13 and 15, and permits the turning of the rail section 21 about the axes of the bolt 30, in the manner shown in Figure 16 so that said rail section 21 may be folded 65 back upon and beneath the rail section 20 as

illustrated in Figures 1 and 17. The raising of the keeper bolt removes the head from the path of movement of the horizontal flange portion of the rail section 21 as is also indicated in Figure 16. It will thus 70 be apparent that by comparatively simple manipulations the rail sections may be collapsed and thus reduced in length with the consequent advantages already referred to. 75

It will be obvious that, so far as the broad aspects of the present invention is concerned, many variations may be possible in the construction and character of the means permitting the collapsing of the rail sections 80 20 and 21 relatively to each other, and consequently I desire to be understood as not limiting myself, so far as the broad aspects of the invention are concerned, to the particular type of coupling means for the rail sections which is shown in the drawings and which has been hereinabove described in detail. Specifically, however, I deem the illustrated and described construction of collapsible rail section to provide a very satisfactory form of side rail collapsing means 85 and have, therefore, also made comparatively specific claims with respect thereto. 90

Having thus described my invention I claim:— 95

1. A side rail for separable attachment between the head and foot ends of a bedstead, said side rail comprising a pair of angle-iron sections adapted to be normally disposed in abutting end to end longitudinally extended relation, an angle-iron coupling means extending across the meeting ends of said sections and within the angle thereof, lateral fastening devices joining the vertical flanges of said respective sections to the vertical flange of said coupling means, vertical fastening means cooperating with the horizontal flanges of said sections and the horizontal flange of said coupling means, at least one of said lateral fastening devices and said vertical fastening means being releasable to permit relative displacement of said sections from normal aligned relation whereby the latter may be moved to a collapsed condition. 100 105 110

2. A side rail for separable attachment between the head and foot ends of a bedstead, said side rail comprising a pair of angle-iron sections adapted to be normally disposed in abutting end to end longitudinally extended relation, an angle-iron coupling means extending across the meeting ends of said sections and within the angle thereof, a transverse fastening means joining the vertical flange of each section to the vertical flange of said coupling means, the abutting end margins of the horizontal flanges of said sections having notches therein to normally oppose each other to form a receiving socket, a corresponding vertically 115 120 125 130

- aligned receiving socket in the horizontal flange of said coupling means, and fastening bolt and nut common to said sections extending through said receiving sockets.
3. A side rail for separable attachment between the head and foot ends of a bedstead, said side rail comprising a pair of angle-iron sections adapted to be normally disposed in abutting end to end longitudinally extended
- 10 relation, an angle-iron coupling means extending across the meeting ends of said sections and within the angle thereof, a transverse fastening means joining the vertical flange of each section to the vertical flange
- 15 of said coupling means, the abutting end margins of the horizontal flanges of said sections having notches therein to normally oppose each other to form a receiving socket, a corresponding vertically aligned receiving socket in the horizontal flange of said coupling means, fastening bolt and nut common to said sections extending through said receiving sockets, at least one of said transverse fastening means being releasable and
- 20 said fastening bolt and nut being likewise releasable to permit relative lateral displacement of said sections from normal aligned relation whereby one of the latter may be turned and doubled back upon the other.
- 25 30 In testimony that I claim the invention set forth above I have hereunto set my hand this 12th day of December, 1927.
